UNITED STATES PATENT OFFICE.

SAMUEL P. WITHROW, OF CINCINNATI, OHIO.

PERAMBULATOR.

SPECIFICATION forming part of Letters Patent No. 700,397, dated May 20, 1902.

Application filed October 21, 1901. Serial No. 79,484. (No model.)

To all whom it may concern:

Be it known that I, SAMUEL P. WITHROW, a citizen of the United States, and a resident of Cincinnati, in the county of Hamilton and State of Ohio, have invented certain new and useful Improvements in Perambulators, of which the following is a full, clear, and exact description, reference being had to the accompanying drawings, which form a part of my specification.

My invention relates to certain improvements in perambulators or baby-carriages, whereby the same may be transformed into a suspensory or basket when it is desired to transfer the child from one place to another, where it would be impossible or inconvenient to "wheel" the carriage, and thus avoid the necessity of unfastening and lifting the child out of the carriage and again replacing and securing it after again reaching a place where the perambulator may be wheeled. It will thus be seen that my invention provides a device whereby a child may be wheeled about from place to place and at the same time a device wherein the child may be conveyed or carried when wheeling it becomes impracticable or undesirable; and the invention will be more fully hereinafter set forth and described in connection with the accompanying drawings, wherein—

Figure 1 is a perspective view of my improved perambulator, showing it in condition to be wheeled. Fig. 2 is a perspective of the same, showing it in condition for carrying as a suspensory or basket. Fig. 3 is a detail view of a modified form of the wheel mounting and controlling mechanism. Fig. 4 is a vertical section taken on the line X X of Fig. 3, showing a portion of the handle and also the pivot-point of the socket in full. Fig. 5 is a detail sectional view of the clamping mechanism for the handle as employed in Fig. 1.

Like letters of reference indicate identical parts in the various figures.

A represents a pair of wheels mounted in the usual manner on the axle B, the axle having its bearing or support in bars or hangers a, of which there are two, one on each side. These bars or hangers a are slidably secured to the side of the basket by means of loops b b, the loops themselves being fastened to the basket by the nuts, as can be seen in Figs.

1 and 2, in the usual manner. The bars or hangers a (illustrated in Figs. 1 and 2) are provided with notches a' at suitable points, 55 which notches are intended for the reception of the ends of spring-controlled dogs b', which are incased in pockets, which may be made integral with the topmost loop b.

C is one of the handles, whose ends are provided with slots, as plainly seen in Figs. 1 and 2, through which the bolt c, Fig. 5, of the ratchet-clamp d passes, the clamp being of the well-known construction, and the whole is clamped and held in place by the butterfly- 65 nut.

I prefer to construct the body or basket with the flaring skirt or pockets D D, which may be made integral with and woven into the body, as illustrated. The flare or bottom 70 of these skirts or pockets is of a degree sufficient to permit the wheels to be entirely drawn up into them, as illustrated in Fig. 2. The basket is also provided with the auxiliary handle or loop E, which is secured to the 75 frame of the basket at the front and rear, as clearly seen in the figures, by weaving the cane or fabric of the loop or auxiliary handle about the frame, though the same may be secured in many other ways.

The basket is of course provided with a seat at a suitable point above the bottom to permit the limbs of the child to rest on the bottom without forcing the knees upward and making the child uncomfortable. This 85 seat may be constructed of cane or any other suitable material and woven into the body of the basket or secured in any of the many suitable ways—as, for instance, it may form an integral part of the basket—and as the construction of the seat may vary it needs no explanation or illustration.

The bottom of the body or basket is provided with a cut-out portion or slot e, Fig. 1, into which the axle B passes when the same 95 is drawn or pressed up, the slot being made of a sufficient depth to permit the axle to pass up far enough to bring the wheels entirely within the pockets D. It is of course understood that this slotway e is at a point immediately over the axle B, which axle will be brought up beneath the seat and in no way interfere with the child in the basket. The upper portions of the skirt or pockets D are

provided with slots, as at *f*, through which the bars or hangers *a* pass to the axle. These slots *f* also permit the ends of the handle *C* to pass through when it is thrown down out 5 of the way and it is desired to carry the basket as illustrated in Fig. 2.

It will be readily understood that when it is desired to wheel the basket the hangers *a* are dropped down to the full extent, as seen 10 in Fig. 1, the spring-controlled dog or latch *b* dropping into the notch and locking the hanger in place.

By reason of the slot the handle *C* may be regulated in its extension outward and may 15 also be placed at any angle desired and there locked in place by the clutch or clamp *d*. It is apparent that the handle *C* may be swung down and made to rest on the ground and there locked in place, thus supporting and 20 holding the basket.

In Fig. 3 I show a modified construction of the method of securing the handle *C* and its connection with the hangers *a*. In this construction the handle *C* passes through a pivoted loop *g*, better shown in Fig. 4 in section, the pivot having its bearing in a plate *h*, which is riveted or secured to the sides of the basket. (See Fig. 4.) Connecting the loop *g* with the hangers *a* in order that it may assume a position coinciding with the position of the hangers *a* is a link *j*, which may be integral with said loop, as it is on a pivot and free to turn, while the opposite end is pivotally connected to the hanger *a*, as seen, thus permitting the 35 hanger to be raised or lowered, as desired. With this construction it is seen that the necessity for the thumb clamp or clutch to hold the handle at the desired angle is obviated by the use of the pivoted loop *g*, through 40 which the handle *C* passes. By the use of this construction the necessity of pressing or dropping the hangers down to bring the wheels into operative position independent of the act of putting the handle *C* into proper position is obviated, as it is apparent that by 45 drawing the handle *C* up through loop *g* sufficiently to permit it to clear the lug or stud *k* and swinging the handle *C* in the proper direction the hangers *a*, by reason of the connection with the loop *g* through link *j*, are necessarily thrown either down or up, according to the direction in which the handle *C* is swung. The link *j*, having a slotted connection with hanger *a*, provides for the slight 55 variation in the distance of the connection between link *j* and hanger *a* from the pivot-point of the loop *g* as the link *j* is swung up or down. After the hangers are dropped down to the limit in order that the wheels 60 may come without the pockets the handle, which is constructed to prevent its entire withdrawal, will impinge against the stud *k*, which is integral with the plate *h* and extends out into the path of the handle, so that 65 when the handle *C* is in that position it may receive pressure and not slip down. The handle in this case may be of sufficient length

to permit all of the mechanism below the spring-controlled dog or latch to be incased in the pockets, as the only part it is necessary to have access to in order to manipulate are the dogs or latches which lock the hangers in place.

I have thus described specifically and illustrated in the drawings what I consider the most desirable forms of construction for accomplishing the desired results, though it will be readily understood that the construction and operation of the parts may be varied—as, for example, the pockets or guards *D* 80 might be made to slide up or down and the axle for the wheels remain stationary, or the pockets or guards may be made to slide or swing to one side or away from the wheels, so as to “free” or expose the wheels, and thus 85 permit of their uninterrupted use, and, furthermore, but one handle might be employed, the real purpose of my invention being, however, the production of a receptacle or device that may be used for wheeling or carrying a 90 child, as might be desired—and I do not wish to limit myself to the exact constructions illustrated in the drawings or herein set forth and described; but

What I do wish to claim as my invention 95 and secure by Letters Patent is—

1. A perambulator or carrier comprising a receptacle for retaining a child, wheels suitably mounted and connected with said receptacle, and mechanism connected with said receptacle whereby the same may be wheeled or carried while in operative condition, substantially as and for the purpose specified.

2. A perambulator or carrier comprising a receptacle provided with a seat, wheels suitably mounted and connected with said receptacle, and mechanism for throwing the perambulator into or out of wheeling condition, and whereby the same may be controlled or carried while in operative condition, substantially in the manner and for the purpose described.

3. A perambulator or carrier comprising a receptacle, wheels, means whereby said receptacle may be carried, or controlled when wheeling, and pockets or guards adapted to incase the wheels for the purpose herein specified.

4. A receptacle mounted on wheels, means for controlling or carrying said receptacle, and pockets or guards wherein the wheels may be incased, substantially in the manner and for the purpose described.

5. A perambulator or carrier consisting of a receptacle provided with a seat, wheels suitably mounted and connected with said receptacle, guards for said wheels, and means whereby the perambulator may be thrown into wheeling condition, and controlled, or vice versa and carried, substantially in the manner and for the purpose described.

6. A perambulator or carrier, consisting of a receptacle mounted on wheels, means for controlling or carrying said receptacle, guards

adapted to incase the wheels, and mechanism whereby the relative position of the parts may be varied, substantially in the manner set forth and described.

7. A perambulator comprising a basket having a seat, wheels arranged below said basket, mechanism slidably connected with said basket whereby the perambulator is controlled and the position of the wheels regulated; pockets on said basket into which the wheels may be drawn, substantially as and for the purpose described.

8. A perambulator or baby-carriage comprising a basket with a rigid handle, pockets on said basket, wheels adjustably secured to said basket, with mechanism for locking the wheels in their adjusted position, and a second handle loosely secured to the basket whereby the perambulator may be propelled, substantially as and for the purpose described.

9. A perambulator or baby-carrier, consisting of a basket formed to provide a seat therein, and having a rigid or auxiliary handle, pockets formed on the lower end of said basket, wheels adjustably secured to said basket

and adapted to be drawn into said pockets, means for locking the wheels in their adjusted position, and a handle loosely secured to said basket adapted to be thrown at any angle to said basket, mechanism for locking said handle in the desired position, and slots in the pockets through which the ends of said handle may pass, substantially as shown and for the purpose described.

10. A perambulator or baby-carriage comprising a basket with a rigid handle, pockets on said basket, wheels secured to hangers having slidable connection with the basket, mechanism for locking the hangers in the desired position, and a second handle loosely secured to the basket and having connection with the hangers whereby the position of the hangers may be changed and the perambulator propelled, substantially as shown and in the manner described.
